DESIGN FOR A CASING FOR GLASS- OR DISH-WASHING MACHINE

Harold E. Weeks, Brooklyn, N. Y.

Application November 29, 1940, Serial No. 96,953

Term of patent 14 years

To all whom it may concern:

Be it known that I, Harold E. Weeks, a citizen of the United States, residing in Brooklyn, county of Kings, and State of New York, have invented a new, original, and ornamental Design for a Casing for Glass- or Dish-Washing Machine, of which the following is a specification, reference being had to the accompanying drawing, forming part thereof.

Figure 1 of the drawing is a perspective view of a casing embodying my invention with the lid in lowered position; and

Figure 2 is a similar view of the said casing with the lid in raised position.

The rear surfaces of the article are substantially plain and the narrow band shown on the right in Figs. 1 and 2, extends uniformly around the rear of the casing to the corresponding opposed pivoted point on the other side.

I claim:

The ornamental design for a casing for glass- or dish-washing machine substantially as shown and described.

HAROLD E. WEEKS.
